UNITED STATES PATENT OFFICE.

ANNIE E. VAN WERT, OF BINGHAMTON, NEW YORK.

DESIGN FOR A BAPTISMAL FONT.

Specification forming part of Design No. 6,159, dated February 25, 1873.

To all whom it may concern:

Be it known that I, ANNIE E. VAN WERT, of Binghamton, Broome county, New York, have invented a Design for a Picture of a Baptismal Font for ornamenting church-windows and fresco-work or for chromos, of which the following is a specification:

The nature of my design is represented in the accompanying photographic illustration, to which reference is made.

A is the font, which surmounts a hexagonal stand, the support of which is ornamented at each angle with a miniature column and an entablature, B, consisting of an architrave, frieze, and cornice, all of which have a corresponding base, C, resting upon a Mosaic pavement. The font A is represented as filled with the choicest selection of flowers, which are scriptural in their significance, and overshadowed by the radiation of the Holy Spirit. The most prominent of these flowers are the Egyptian calla, Persian flowers, lily of the valley, star of Bethlehem, and diaclotia or bleeding heart, which are emblematical of the birth, passion, and resurrection of Christ.

What I claim as my invention is—

A design representing the font A filled with the above-named flowers, the stand and entablature B, support and base C resting upon the Mosaic pavement, all ornamented and arranged as illustrated and described.
